US00D756761S

(12) **United States Design Patent**
Frick et al.

(10) **Patent No.:** **US D756,761 S**
(45) **Date of Patent:** **** May 24, 2016**

(54) **QUICK CONNECT COUPLING CLIP**

(71) Applicant: **Moen Incorporated**, North Olmsted, OH (US)

(72) Inventors: **Timothy A. Frick**, Brunswick, OH (US); **W. Randall Tucker**, Oberlin, OH (US)

(73) Assignee: **Moen Incorporated**, North Olmsted, OH (US)

(**) Term: **14 Years**

(21) Appl. No.: **29/490,894**

(22) Filed: **May 15, 2014**

Related U.S. Application Data

(63) Continuation of application No. 13/468,515, filed on May 10, 2012, now Pat. No. 8,764,068.

(51) **LOC (10) Cl.** **08-08**

(52) **U.S. Cl.** **D8/382**
USPC **D8/382**

(57) **CLAIM**

The ornamental design for a quick connect coupling clip, as shown and described.

DESCRIPTION

FIG. 1 is a perspective view of a quick connect coupling clip of the new design;

FIG. 2 is a front elevational view of the quick connect coupling clip of FIG. 1, the rear elevational view being a mirror image thereof;

FIG. 3 is a left side elevational view of the quick connect coupling clip of FIG. 1;

FIG. 4 is a right side elevational view of the quick connect coupling clip of FIG. 1; and,

FIG. 5 is a top plan view of the quick connect coupling clip of FIG. 1.

The broken lines in the drawings illustrate portions of the quick connect coupling clip and form no part of the claimed design.

1 Claim, 5 Drawing Sheets
